Hugh Mulhollen,

*By C. M. Alexander,
his Atty.*

UNITED STATES PATENT OFFICE.

HUGH MULHOLLEN, OF FOSTORIA, PENNSYLVANIA.

HYDRAULIC PROPELLER.

SPECIFICATION forming part of Letters Patent No. 247,679, dated September 27, 1881.

Application filed August 16, 1881. (Model.)

To all whom it may concern:

Be it known that I, HUGH MULHOLLEN, of Fostoria, in the county of Blair, and in the State of Pennsylvania, have invented certain new and useful Improvements in Propellers for Vessels; and I do hereby declare that the following is a full, clear, and exact description thereof, reference being had to the accompanying drawings, and to the letters of reference 10 marked thereon, making a part of this specification.

This invention relates to propellers for boats wherein pistons reciprocate inside of cylinders which are submerged, and which may be arranged at the stern, at the sides, or at the bow 15 of a boat.

The nature of my invention and improvement consists, mainly, in providing each piston-cylinder with a side outlet for water, in combination with cylindrical valves acted on by springs and arranged back of the pistons, said valves being intended for closing the side outlets at certain times, and allowing the escape of any water which may leak into the cylinders 25 back of the pistons. I also employ air-tubes for the cylinders, so arranged as to allow the free escape of air, as will be hereinafter explained.

In order to enable others skilled in the art 30 to which my invention appertains to make and use the same, I will proceed to describe its construction and operation, referring to the annexed drawings, in which—

Figure 1 is a plan view of two propellers, 35 their piston-rods, crank-shaft, and pitman-rod; Fig. 2, a longitudinal section taken vertically through one of the propellers. Fig. 3 is a section taken vertically and transversely through the cylinders in the plane indicated by the 40 dotted line $\alpha\alpha$ on Fig. 1.

The letters A A designate two cylinders, which are constructed with closed heads $a a$, and with side outlets, $b b$, leading into chutes B B, that extend to the open ends of the cylinders outside thereof.

The outlets $b b$ are located near the closed heads of the cylinders, and in or nearly in the same vertical plane with these water-outlets are tubular outlets B', which allow a free escape of air from the cylinders A back of the pistons, and which should be of such length 50 as to extend well above the highest water-level.

The two cylinders A A are suitably mounted either at the stern of a boat or at any other 55 desired point thereof. Inside of each cylinder A is a piston, C, which is suitably packed, and which is provided with a piston-rod, D, that passes through a stuffing-box applied to the head a . The piston-rods are connected by 60 jointed rods E to a crank-shaft, F, which receives rotation from any convenient prime motor.

It is not intended that the pistons shall be packed so tightly in their cylinders as shall 65 exclude the possibility of water getting between them (the pistons) and the cylinder-heads, especially when the boat is stationary for some time. I get rid of this water which is between the piston-heads and pistons by the 70 following contrivance:

D' D' designate two cylindrical valves or flanged heads, arranged between the pistons and cylinder-heads and packed loosely in the cylinders. The piston-rods D play freely 75 through the valves D', and these valves are connected to the cylinder-heads by means of springs F'. (Shown in Fig. 2.) The valves are held by the springs F', so as to close the openings b . When there is an accumulation 80 of water back of the pistons—*i.e.*, between the pistons and the valves—and the former are caused to move back, the valves will also recede and allow the water to escape through the outlets b and chutes B. As the pistons make 85 their return or forward strokes the springs F' will cause the valves to close the outlets b .

By the mechanism shown for operating the pistons it will be seen that they receive alternate forward and backward strokes.

Having described my invention, I claim—

In a marine propeller consisting of a cylinder, A, an outlet, b , and a chute, B, and a piston, C, the combination therewith of the cylindrical valve D' and its spring F', substantially 95 in the manner and for the purpose described.

In testimony whereof I affix my signature, in presence of two witnesses, this 23d day of July, 1881.

HUGH MULHOLLEN.

Witnesses:

H. H. KLINE,
ROBERT WARING.
